TRANSMISSION MECHANISM FOR POWER
BOOMS OF CONCRETE PAVERSAxel E. Lundbye, Nunda, N. Y., assignor to The
Foote Company, Inc., Nunda, N. Y., a corpora-
tion of Delaware

Application September 11, 1935, Serial No. 40,178

1 Claim. (Cl. 198—119)

My invention relates to new and useful improvements in transmission mechanism for power booms of concrete pavers, and has for an object to provide a transmission mechanism on which a 5 paver boom may be pivotally mounted wherein the boom may be automatically and/or mechanically traversed and manually, as well as power-operated, raised and lowered. The transmission is so arranged that power may be conveniently transmitted to an endless conveyor for operation thereof and also utilized to advance or retract different forms of distributing carriages on the boom.

In a co-pending application filed by me on May 25, 1935, bearing Serial Number 23,490, for Concrete pavers, a power boom is shown mounted on this transmission mechanism, there being in that instance a form of carriage wherein the conveyor belt changes its direction at a point intermediate its opposite ends, so that the concrete or aggregates may be distributed at any desired point 10 along the boom.

In another co-pending application filed by me on September 11, 1935, bearing Serial Number 40,179, for Distributing means for concrete pavers, 15 this transmission mechanism is also shown in combination with a boom and traveling carriage wherein the carriage is provided with abutment means to dam the concrete or aggregates and deflect the passage thereof at either or both sides 20 of the boom into delivery chutes.

The present application relates to the transmission mechanism per se, a portion of the endless conveyor, a portion of the means for operating a carriage as well as a portion of the means 35 for traversing the boom, which is also shown and described to illustrate the manner in which the transmission is used.

Still another object of the invention is to provide a transmission or power transmission mechanism that may be readily positioned on different 40 styles of pavers wherein an endless conveyor belt is used rather than the old type of boom and bucket.

As is well known, a certain form of transmission mechanism is needed for paver booms, due to 45 the necessity of continuously traversing the boom, to the fact that the boom has to be raised and lowered, and finally to the fact that power must at all times be applied to the conveyor belt, regardless of the angular position of the boom.

50 Still another object of the invention, therefore, is to provide a compact transmission mechanism wherein the power is derived from the power plant of the paver and may be distributed to the boom and its several operating mechanisms.

55 With these and other objects in view, the inven-

tion consists in certain new and novel arrangements and combination of parts as will be herein-after more fully described and set forth in the claim.

Referring now to the drawings showing a preferred embodiment,

Fig. 1 is a side elevation of the transmission mechanism, a fragmentary portion of the paver frame and a fragmentary portion of the boom;

Fig. 2 is a top plan view of the transmission 10 mechanism, parts being removed and parts being broken away for the sake of clearness;

Fig. 3 is a vertical transverse sectional view 15 taken on the line 3—3 of Fig. 1 with parts of the boom and conveyor being shown in elevation; and

Fig. 4 is a fragmentary top plan showing a portion of the conveyor belt, the clutch for operating the same, the drums and their mechanism for operating the carriage along the boom, and the clutch for traversing the boom.

Referring now more specifically to the several views, and for the moment to Fig. 1, there may be seen a fragmentary portion of the main frame 1 of the paver, while extending downwardly therefrom may be seen the channels 2 and 3, on which 25 is mounted the transmission mechanism 4. Also at the top of the view may be seen the chute, gate, and boot for regulating the flow of aggregates to the endless conveyor. These elements do not enter into the invention, so are not described in 30 detail.

Extending inwardly of the transmission is the main power drive shaft 5, that is operated from the power plant of the paver. Besides driving the transmission 4, the power shaft also drives the 35 stub shaft 6 through the sprocket chain 7, the shaft 6 having the pinion 8 thereon which, in turn, operates the clutch 9 through the operation of the slip collar 10 of the clutch, so that the worm shaft 11 may be rotated in either of the desired directions, as will be readily apparent. The slip collar 10 is operated through the arm 12 and connecting rod 13, a fragmentary portion of the rod being shown. The worm shaft 11 through the worm 14 operates the traverse gear 15 in the transmission 45 4, which will be later described, so that by moving the control rod 13 to operate the clutch, the boom may be traversed to the right or left, as desired.

Referring now for the moment to Fig. 3, it will be noticed that the transmission 4 mounted on 50 the channels 3 comprises an upper rotatable casing 16 and a lower stationary casing 17, and let us consider first the lower casing and its parts.

The power shaft 5 enters the transmission housing through the reinforced opening 18 (Fig. 55

1) and is provided with a pinion 19 thereon, which meshes with the bevel master gear 20 which, in turn, is mounted on the lower end of a vertical shaft 21.

5 There may also be seen the bottom pan 22, which is bolted to the circular wall 23 formed on the bottom plate 24 of the lower part 17 of the transmission, so that the pinion and gear just referred to may be greased, removed, or 10 replaced if ever damaged.

15 Also extending upwardly from this plate 24 and centrally thereof is the integral hub casing 25, which terminates at 26, and in which extends the pintle or hub 27 formed on the plate 28, which plate and pintle constitute a portion of the upper rotatable casing or portion 16 of the transmission mechanism.

20 It is through the pintle 27 and likewise through the plate 28 that the vertical shaft 21 extends. There may also be seen the mitre gear 29 mounted on the upper end of the shaft 21 which, in turn, meshes with the gear 30 mounted on the cross power shaft 31 which is, in turn, mounted in the split bearings 32 and in the extensions 44, 25 later on referred to.

25 In Figs. 2 and 3, there is shown the rectangular upper housing 33 formed on the plate 28 for these last-mentioned gears, while on this housing there is fitted a removable cover plate 33', so that the gears are readily accessible.

30 At the outer ends of the shaft 31 are provided the sprocket wheels 34 for transmitting power to the shaft 46.

35 Now the traverse gear 15, heretofore-mentioned, which is operated by the worm 14, is secured by the bolts 35 to the downwardly extending walls 28' of the plate 28 of the upper portion 16 of the transmission, the periphery of the gear 15 being boxed in by the cover plate 36 that is 40 fitted, as at 37, to the upwardly extending wall 38 of the plate 24 of the lower casing 17. Thus, when the gear 15 is rotated through the action of the worm 14, the plate 28 with its pintle 27 and its gear 15 will be rotated with reference to the hub casing 25 and the lower part of the transmission, and as the boom is carried by this 45 part of the transmission, the boom will rotate with the gear.

50 By having the vertical shaft 21 the central pivotal axis of the rear end of the boom, any traversing of the boom will not affect the operation of the two gears 29 and 30, as the gear 30 will travel around the gear 29 on a transverse movement of the boom. Likewise, as the shaft 55 55 31 is the central horizontal pivotal axis of the rear end of the boom, the boom may be elevated or lowered, pivoting in the bearing housings 44' of the extensions 44, as shown. In other words, the transmission 4 is so arranged as to provide 60 a central pivotal axis for traversing, while the cross shaft permits a pivotal raising or lowering of the boom. There may also be seen the further strengthening plates 43 extending from the rotating part 16 of the transmission housing to the extensions 44 of the channels 42 of the boom.

65 It will be noticed that the channels 42 of the boom have the downwardly extending bearing housings 44' in which the shaft 31 is mounted, and it is in these bearings that the boom may be elevated or lowered, as just described.

70 As far as the specification has proceeded, it will be seen that by providing a centrally located transmission of the type described at the discharge end of the paver, the boom may be mounted thereon and is capable of being traversed and

is also capable of being elevated while, regardless of its position, power may at all times be transmitted to the shaft 31 with its sprockets 34 at the end thereof.

5 Now supported on the channels 42 of the boom are the further bearings 45 in which is mounted the shaft 46 which, in turn, has the sprocket wheels 47 at its outer ends, over which run the chains 48 and which, in turn, are driven by the sprockets 34 which are mounted, as will be remembered, on the main cross shaft 31 and driven by the shaft 21 through the pinion and gears from the main power drive of the paver.

10 These chains and sprockets are well illustrated in Fig. 1, and their purpose is to drive an endless conveyor on the boom and also to furnish a means for driving drums at the opposite sides of the boom for advancing or retracting a carriage along the boom, as shown in an application filed by me on May 25, 1935, bearing Serial Number 23,490, for Concrete pavers. These drums can be used in driving a different form of carriage, as shown in a further companion application filed by me on September 11, 1935, bearing Serial Number 40,179, for Distributing means for concrete pavers.

15 As the mechanism for operating the carriage positioning drums is fully described in the companion applications, it will be mentioned but briefly here.

20 Referring for the moment to Figs. 3 and 4, there will be noticed a bevel gear 49 which, in turn, meshes with the pinion 50 mounted on the shaft 51, on the far end of which is the pinion 52 meshing with the loosely mounted mitre gears 35 53 and 53'. There is the usual sliding clutch collar 54 between the gears, so that the shaft 55, which is operated by this clutch collar, may be driven in either one of two desired directions.

25 On the outer end of the shaft 55 are the drums 56, on which endless cables 57 will be threaded, which extend out to a carriage (not shown), so that the same may be advanced and retracted along the boom, depending on the direction of rotation of the shaft 55. The clutch is operated 45 through the arm 58 and its operating rod 59 so that a movement of this rod will cause the drums to travel in the desired direction, depending on the direction of movement of the said rod 59.

30 This last-mentioned mechanism is actually not 50 a part of the transmission, but the brief description is set out to show the advantages of a transmission of this kind.

35 I have not shown a clutch on the power shaft 5 to the transmission but, of course, one is provided, so that the power shaft 5 will be actuated only when it is desired to operate the conveyor belt which is, in turn, operated by the drum 61 mounted on the power shaft 46.

40 I have also only fragmentarily shown the boom 60 structure, as it does not form the gist of the present invention.

45 As the structure of the transmission has been set out rather in detail, a brief description of the operation is only considered necessary.

50 If it is desired to traverse the boom, the power shaft 5 will be set in motion and an operation of a handle controlling the rod 13 in either direction will cause the worm 14 and the gear 15 to traverse the boom to the required position, as 70 will be readily understood. The manually or power-operated drums for elevating the boom are not shown, but as the boom is mounted at its rear end with the shaft 31 as a pivotal point, it will be readily understood that the boom is ca- 75

pable of being raised or lowered. Continuing, the operation of the power shaft 5 through the pinion 19 and gear 20 will revolve the shaft 21 and, through the gears 29 and 30, rotate the shaft 31 and its sprockets 34 to, in turn, through the chains 48, operate the sprockets 47 and drive the shaft 46 with its drum 61 thereon to operate the conveyor belt 60. Likewise, an operation of the shaft 46 through its gears 49 and 50 will drive the clutch gears 53 and 53', and by shifting the lever 58, the slip collar 54 will lock the desired gear to the shaft 55 to, in turn, operate the drums 56 and their cables 57.

It will be understood that the shape of the 15 housings for the transmission parts 16 and 17 may be arranged to fit different types of booms and that I do not wish in any way to be limited to the exact construction shown.

Finally, it will be seen that by providing a 20 flexible form of transmission, as shown, power may be transmitted to the several parts on the boom at all times, regardless of the angle of elevation of the boom or of the position of traverse.

Having thus described my invention, what I claim as new and desire to secure by Letters Patent is:

A transmission for a paver boom including an upper and a lower housing, the lower housing being stationary and the upper housing rotatable therein, a cross shaft mounted in said upper housing and said cross shaft extending into bearings mounted on the boom independently of the transmission, a vertical shaft in said transmission arranged to form a central pivotal axis for the rear end of the boom, a gear and a pinion respectively mounted on the vertical shaft and cross shaft, a worm and a gear for rotating the upper part of the housing and thereby the boom, and 15 the worm adapted to be operated by a clutch, driving means connected with the said vertical shaft for rotating the cross shaft, sprocket means on the outer end of said shaft, and bearings at the outer end of said cross shaft permitting the 20 boom to be elevated and lowered without affecting the driving means of the transmission.

AXEL E. LUNDBYE.
